PIVOTED DIAL CALIPERS

Carlos Moerman, Richmond, Calif.

Application June 22, 1944, Serial No. 541,529

4 Claims. (Cl. 33—148)

1

This invention relates to outside calipers, the main object being to provide a calipers arranged for calibration of shafting or other round surfaces and having means for visually showing the measurement obtained in inches, tenths and thousandths, or similar relatively close figures.

A further object is to provide a calipers as above, in which the measurement indicator is in the general form of a watch or clock face, making it extremely easy to read any measurement obtained.

Another object of the invention is to obtain the above results with a minimum number of parts composing the structure.

Another object is to provide a structure that can be made small, compact and light in weight.

Figure 1 is a sectional plan view of the device.

Figure 2 is a plan view of the instrument dial.

Figure 3 is a sectional side elevation of the indicating instrument.

Referring to the numerals of reference on the drawings, the calipers comprise a pair of caliper legs 1 and 2, formed with ball shaped terminals 3 on their outer end for engagement with the work.

The legs are pivoted at their other ends in spaced relation as at 4 in a cylindrical case 5 adjacent the periphery thereof. The free end portions of the legs project thru an arcuate slot 6 in the case. The inner ends of the legs are provided with segmental gears 7 which are concentric with pivots 4 and constantly mesh with each other and cause the legs 1 and 2 to move simultaneously.

Within the case, leg 1 is formed with an extension 8 beyond its pivot 4, which carries an arcuate rack gear 9 meshing with a pinion 10 fixed on a shaft 11 journaled in a frame 12 within the case.

A gear 13 fixed with shaft 11 meshes with a pinion 14 fixed on another shaft 15 journaled in frame 12. A gear 16 fixed on shaft 15 meshes with a pinion 17 mounted on an actuator shaft 18 journaled in frame 12 centrally of case 5.

The outer face of one frame member 12 is formed with a dial plate 19 thru which shafts 11, 15 and 18 project; the shafts ends being provided with indicator fingers or needles 20, 21 and 22 respectively. These needles read on dials 23, 24 and 25 on the dial plate which are graduated in inches tenths and thousandths respectively; it being understood that the various pinions and gears in the train above described, including gears 1, are so relatively proportioned that with relative movement between legs 1 and 2, the distance between terminals 3 will be correctly indicated on the dials.

In order to turn the legs so as to separate or

2

bring the heads 3 together, shaft 18 is provided with a finger knob 26 on its end opposite the dial plate and outside the case. In order to gain operating speed, so as to provide a quicker leg movement than could otherwise be obtained, a flywheel 27 is fixed on shaft 18 within the case. All moving parts of the operating, control and indicating mechanism, except the knob, are enclosed in the case; the dial plate and needles being covered by a transparent disc 28.

While the form of mechanism herein shown and described is admirably adapted to fulfill the objects primarily stated, it is to be understood that it is not intended to confine the invention to the one form of embodiment herein disclosed, as it is susceptible of embodiment in various forms, all coming within the scope of the claims which follow.

What is claimed is:

20. 1. Calipers of the character described having in combination a case, a pair of legs pivotally supported at one end within said case and having work-engaging portions projecting from the latter, a plurality of separate indicating dials carried by said case each dial having data thereon indicating predetermined increments of measurement, the data on each dial being proportioned to the data of all of the other dials, a train of gearing mounted within the case and including members concentrically mounted relative to the respective dials, pointers for the respective dials, each operatively connected with said train of gearing and movable over the dial, an actuator shaft for one of said pointers, said actuator shaft having a driving engagement with said train of gearing, said shaft having an extension projected through the case to the exterior thereof, so as to be accessible for manual operation, and means operated by rotative adjustments of said actuator shaft for imparting concurrent pivotal movements to said arms.
2. Calipers of the character described having in combination a case, a pair of legs pivotally supported at one end within said case and having work-engaging portions projecting from the latter, a plurality of separate indicating dials carried by said case each dial having data thereon indicating predetermined increments of measurement, the data on each dial being proportioned to the data of all of the other dials, a train of gearing mounted within the case and including members concentrically mounted relative to the respective dials, pointers for the respective dials, each operatively connected with said train of gearing and movable over the dial,

a fly-wheel connected with said train of gearing, manually operable means for imparting rotative movement to said train of gearing, and means actuated by said train of gearing for imparting concurrent proportional adjusting movements to said legs.

3. Calipers of the character described having in combination a case, an actuator shaft rotatively mounted in said case and having one end projecting from the latter so as to be accessible for manual rotative adjustments, a series of other shafts also rotatively mounted in said case, predeterminedly proportioned gearing connecting said actuator shaft with the other shafts, so that rotative adjustment of said actuator shaft will impart proportionate adjustment to the other shafts, measurement indicia arranged concentrically around each of said shafts, the indicia for each shaft designating increments of measurement proportioned to the increments of measurement of all of the other indicia, pointers secured to and rotatable with all of the respective shafts so as to travel over the respective indicia, a pair of caliper legs each pivotally mounted at one end within said case and having work-engaging portions projecting from the latter, and means operated by rotative adjustments of one of the gears of said gearing for imparting relative adjusting movements to said legs.

4. Calipers of the character described having in combination a case, a pair of shafts in said case, means for imparting rotary motion from one of said shafts to the other, an actuator shaft rotatively mounted in said case and having one end projecting from the latter so as to be acces-

5
10
15

sible for manual rotative adjustments, means operated by the actuator shaft for imparting proportionate concurrent movement to one of the other shafts, a fly wheel on said actuator shaft, measurement indicia arranged concentrically around each of said shafts, the indicia for each shaft designating increments of measurement proportioned to the increments of measurement of all of the other indicia, pointers secured to and rotatable with all of the respective shafts so as to travel over the respective indicia, a pair of caliper legs each pivotally mounted at one end within said case and having work-engaging portions projecting from the latter, and means operated concurrently with adjustments of said shafts for imparting concurrent relative adjusting movements to said leg.
